UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

MACHINE FOR FORMING AND GLUING PAPER CUPS.

Application filed July 20, 1923. Serial No. 652,763.

To all whom it may concern:

Be it known that I, CESARE BARBIERI, a subject of the King of Italy, and a resident of the city of New York, in the county of 5 New York and State of New York, have invented certain new and useful Improvements in a Machine for Forming and Gluing Paper Cups; and I do hereby declare that the following is a full, clear, and exact description of the same, reference being had to the accompanying drawings, and to the numerals of reference marked thereon, which form a part of this specification.

This invention relates more particularly 15 to an improved automatic paper cup forming machine and more particularly to mechanisms for the machine whereby paper cup blanks are automatically fed singly into the machine and into the field of operation 20 of an adhesive applying pad which acts at a predetermined time to apply adhesive to a portion of the blank in a determined configuration, after which the blank is advanced between forming dies one of which is 25 spirally grooved so that while the blank is being wrapped around the other die the margin of the adhesived portion of the blank is not pressed against the main portion of the blank, thereby causing a paper cup to be 30 formed wherein none of the adhesive is squeezed out from between overlapping portions of the formed cup.

It is an object of the invention to provide 35 an automatic adhesive applying mechanism for a paper cup forming machine whereby adhesive is applied to a blank at a predetermined distance from one of the margins thereof so that when the blank is formed into a cup the adhesive will not be pressed 40 out from between the overlapping portions of the blank.

It is also an object of the invention to provide a cup forming machine wherein the cup blanks while being advanced toward the 45 forming dies are acted upon by an adhesive applying pad which acts to apply adhesive to the blanks in a patch of a predetermined shape and at a distance from one of the margins thereof so that when the blanks are shaped into cups and stacked they will not stick to one another due to portions of the adhesive being squeezed out from between overlapping portions of the blanks.

It is a further object of this invention to

provide a cup making machine with a blank 55 feed mechanism adapted to first remove a blank from a magazine and then advance said blank into a position to be stamped by an adhesive applying pad before being transferred onto a reciprocating table to be 60 fed between cup forming dies.

It is furthermore an object of the invention to provide a cup forming machine with forming dies one of which is spirally grooved to prevent pressure from being applied to the edge of the adhesived margin of 65 a cup blank being formed into a cup around the other of said dies.

Still another object of the invention is to provide a cup forming machine wherein a 70 blank after being removed from a magazine is stamped by an adhesive applying pad and then gripped by a gripping mechanism and transferred to a lower level onto a reciprocating table below resilient retainers to be 75 advanced between forming dies and formed into a cup thereby.

It is a further object of the invention to provide a cup making machine wherein formed glued cups, when discharged from 80 forming dies, are deposited to fall through a curved chute before reaching a cup stacking tube to afford time for the glue to set before the formed cups are nested one within the other in a cup holder which is adapted 85 to be lowered within the stacking tube each time a formed cup is delivered thereto.

Another object of the invention is the construction of a cup forming machine provided with an adhesive supply roller against 90 which a rotatable reciprocating adhesive distributing roller is adapted to engage to receive a supply of adhesive and then roll over a reciprocating pad which is adapted 95 to stamp a cup blank with a film of adhesive before the cup blank is advanced between the cup forming dies of the machine.

It is also an object of this invention to provide a cup making machine with a cup stacking mechanism having a long chute 100 through which the finished cups pass before entering a stacking tube in which a cup receiver is adapted to be automatically lowered each time a cup is received, said chute being provided with a pivoted shutter adapted to close the lower end of the chute when in closed position to form a stop for cups in 105 order that a stack of cups may be removed

from the stacking tube without necessitating stopping of the machine.

It is an important object of this invention to provide an improved automatic adhesive applying mechanism for a cup making machine, said mechanism being operable from the machine and timed to act at a predetermined time during a blank feeding operation to stamp a cup blank with a film of adhesive in advance of the action of a transfer mechanism which transfers the adhesive blank onto a reciprocating table which advances the blank into the field of operation of cup forming dies.

Other and further important objects of this invention will be apparent from the disclosures in the specification and the accompanying drawings.

The invention (in a preferred form) is illustrated in the drawings and hereinafter more fully described.

On the drawings:

Figure 1 is a top plan view of a cup making machine embodying the principles of this invention.

Figure 2 is a side elevation thereof.

Figure 3 is a fragmentary front elevation of the machine.

Figure 4 is a fragmentary longitudinal section taken on line 4-4 of Figure 1.

Figure 5 is a fragmentary rear elevation of the machine taken on line 5-5 of Figure 1.

Figure 6 is an enlarged horizontal sectional view taken on line 6-6 of Figure 2.

Figure 7 is an enlarged detail view taken on line 7-7 of Figure 1.

Figure 8 is a fragmentary detail view taken on line 8-8 of Figure 1.

Figure 9 is an enlarged detail view taken on line 9-9 of Figure 6.

Figure 10 is a detail view taken on line 10-10 of Figure 4.

Figure 11 is an enlarged fragmentary detail section taken on line 11-11 of Figure 1.

Figure 12 is a detail section taken on line 12-12 of Figure 11.

Figure 13 is an enlarged detail section taken on line 13-13 of Figure 1 showing the operation in dotted lines.

Figure 14 is a detail section taken on line 14-14 of Figure 4 with parts in elevation.

Figure 15 is a fragmentary detail view taken on line 15-15 of Figure 2.

Figure 16 is an enlarged detail section taken on line 16-16 of Figure 1 with parts omitted.

Figure 17 is a fragmentary side elevation of the cup receiving and stacking mechanism of the machine.

Figure 18 is a side elevation of the cup forming and presser dies showing a cup blank engaged around the forming die.

Figure 19 is an enlarged fragmentary detail section taken on line 19-19 of Figure 18.

Figure 20 is an enlarged transverse section of the blank discharge roller taken on line 20-20 of Figure 1.

As shown on the drawings:

The reference numeral 1 indicates a machine frame having supported thereon a head or standard 2. Mounted in suitable bearings in the machine frame 1 is a main driving shaft 3 upon which are mounted fast and loose pulleys 4 and 5 adapted to be driven by a belt. A driving gear 6 is keyed to the shaft 3 and meshes with a main operating gear 7. Connected to be driven from the drive shaft 3 is a cup forming cone or die 8. The gear 7 is mounted on a shaft supported in bearings 9 on the machine head 2. Said shaft has mounted on the inner end thereof a beveled cam 10 (Fig. 2) which coacts with a beveled roller 11 supported on an extension of a sleeve 12 pivoted on the machine head at 13. The sleeve 12 affords a bearing for a shaft 14 having a cup presser cone or die 15 fixed on the lower end thereof for coaction with the forming die 8. The presser die 15 is provided with a spiral groove 16 (Fig. 18) adapted to engage over the margin 17 of the overlapping portion 18 of a cup blank 19 when being formed into a cup on the forming die 8, as illustrated in Figures 18 and 19. Fixed on the shaft 14 is a beveled gear 20 adapted to mesh with a similar beveled gear mounted on the shaft on which the forming die 8 is mounted. A yoke 21 is provided on the head 2 and has co-operating therewith a coiled spring 22 adapted to resiliently hold the presser die 15 in contact with the forming die 8. A scraper mechanism 23 is provided to coact with the presser die 15.

The cup forming and discharge mechanisms of this invention are similar to those illustrated and described in applicant's co-pending application for patent for an "automatic cup forming machine," Serial No. 259,986, filed October 28th, 1918, and are therefore not described and illustrated in detail in this application.

Pivottally connected eccentrically to the large gear 7 is one end of a connecting rod 24, the other end of which is pivoted to an arm 25 fixed at one end of a rod or shaft 26 supported in bearings 27 fixed on the frame 1 and also projecting through a bearing 28 formed on a bracket 29 of the machine frame. An arm or lever 30 is pivoted on the other end of the rod 26 to the outside of the bracket 29 and has the upper end thereof pivotally connected to operate an inclined reciprocating blank feed table 31. The slide table 31 is mounted to slide on a pair of parallel guide rods 32 beneath a stationary table 33 having an opening 34 therein. The stationary table 33 is supported on the machine frame in a horizontal position above the level of the inclined slide table 31 and

has positioned thereabove a blank guide plate 35 provided with an upturned curved flange 36. The slide table 31 is adapted to be reciprocated by the arm or lever 30 in a plane substantially that of the meeting surfaces of the cup forming dies 8 and 15. The table 31 has a wide head portion 37 provided with a plurality of projections 38 having upturned fingers or tips 39. A curved cup blank stop 40 is formed along one margin of the table head 37 behind a blank supporting pin 41 which is of a height equal to that of the fingers 39. An extension plate 42 is provided at one side of the table head 37 and has a plurality of blank supporting pins 43 thereon. An angled blank stop flange 44 is formed along two edges of the table head extension 42.

The table actuating arm 30 has connected thereto one end of a coiled spring 45, the other end of which is connected to an adjusting screw 46. The screw 46 is mounted on an arm or plate 47 having a hub fixed on the shaft 26. Integrally formed on the plate 47 is an extension 48 which is held in contact with a screw 49 which projects through a boss 50 formed on the arm 30.

As illustrated in Figure 10, the slideable table 31 has slidably supported on the under side thereof a slideable bar 51 which is held extended from beneath the advance edge of the table head 37 by a coiled spring 52. The projecting bar 51 serves to support the extending tip of a cup blank while the slideable table is moving forward into a position to feed a blank between the forming dies 8 and 15. The slideable bar 51 is, however, arrested in its forward movement before it comes in contact with the forming dies, while the slideable table continues to move forward to insure a positive feed of the blank between the dies.

The blank feeding mechanism is operated from the large gear 7 which has meshing therewith a gear 53. The gear 53 is fixed on one end of a shaft 54 supported in bearing brackets 55 and 56. The bearing bracket 55 is fixed on the machine frame 1, while the bearing bracket 56 is secured upon one of the uprights 57 of an auxiliary framework 58 mounted on one side of the frame 1. A beveled pinion 59 is fixed on the inner end of the shaft 54 and meshes with a beveled gear 60. The beveled gear 60 is fixed on the inner end of a shaft 61 supported by the uprights 57 of the auxiliary frame 58. Secured on the shaft 61 to the outside of the outer upright 57 is a gear 62. A sprocket wheel 63 is mounted on the outer end of the shaft 61. The gear 62 is in mesh with a gear 64 which is mounted on one end of a shaft 65 supported by the frame uprights 57. Fixed on the shaft 65 between the uprights 57 is a blank feed reel comprising a plurality of spaced disks 66

connected by oppositely disposed bars 67. Secured to each reel bar 67 is a curved friction pad 68 made of rubber or other suitable material (Fig. 20). The blank feed reel is positioned to act through an opening 69 in a magazine base board 70 to permit the feed reel pads 68 to frictionally engage the lowermost cup blank in a blank holding magazine. The blank holding magazine is supported on the board 70 and comprises a plurality of guide posts 71, the lower ends of which are secured to cylindrical blank supporting bosses 72 fixed on the board 70 with the upper surfaces thereof on a level with the under surface of the stationary table 33. Mounted on the board 70 adjacent one of the bosses 72 is a block 73 having a pin 74 secured thereon to engage against the margin of the lowermost cup blank in the magazine. Secured to one of the uprights 57 is a shaped blank guide band 75 to which a plurality of upright blank guide bars 76 are secured. Also secured to the same upright 57 to which the band 75 is secured is an inclined blank tip guide 77 positioned to clear the blanks in their downward movement in the magazine but adapted to afford a guide beneath which the tips of the cup blanks are adapted to move when the cup blanks are being fed longitudinally out of the bottom of the magazine.

Projecting transversely across the lower portion of the cup blank magazine is a rod 78 supported by the uprights 57. Secured on the rod 78 are a pair of parallel arms 79 which normally rest upon the board 70 with the upper surfaces of said arms on a level with the tops of the blank supporting bosses 72. Engaged on the outer end of the rod 78 is a collar or sleeve 80 having projecting therefrom a short crank arm 81. Pivoted on the end of the crank arm 81 is one end of a long bar 82, the other end of which is provided with a projection or pin 83 (Fig. 15) for coaction with a cam block 84. The cam block 84 is secured to the pivoted end of a transverse bar or bracket 85. A radially directed stop pin 86 is secured to the pivoted end of the bracket 85 for coaction with the bar 82 when the bracket 85 is swung upwardly about a shaft 87 by means of a handle 88. The shaft 87 projects through a hub 89 on the bracket 85 and is supported on a hub 90 fixed on an upright stationary frame plate 91. Formed on the outer side of the inner end of the bracket 85 is a boss 92 having a passage 93 therein for receiving one end of a latch bolt 94. The latch bolt 94 slidably projects through a passaged boss 95 formed on the frame plate 91 and is provided with two spaced circumferential grooves 96 and 97 (Fig. 13) for coaction with a spring impelled detent 98 mounted within the boss 95. A hand knob 99 is

provided on the outer end of the latch bolt 94 to facilitate operation of said latch bolt to release the bracket 85 or hold said bracket locked in a normal lowered position with 5 the latch bolt in its innermost position, as illustrated in full lines in Figure 13, with the detent 98 engaged in the groove 97. Secured to the bottom of the bracket 85 is the blank guide plate 35. Mounted upon 10 the top of the blank guide plate 35 is an electrical heater 100.

When a cup blank is moved out of the magazine onto the stationary table 33 it is advanced between a lower feed roll 101 and 15 an upper feed roll 102. The lower feed roll 101 is mounted on a shaft 103 supported on the machine frame and having a pinion 104 fixed on one end thereof. The pinion 104 is in mesh with an upper pinion 105 20 which is fixed on one end of a shaft 106 on which the upper roll 102 is mounted. The upper shaft 106 is journaled in spring impelled blocks which are slidable in an arched frame or yoke 107 formed or mounted 25 upon the machine frame uprights 57. The feed rolls 101 and 102 are driven by a gear 108 which meshes with the pinion 104 and is mounted on a stud shaft 109 on which a small gear 110 is also mounted. 30 The small gear 110 is in mesh with the gear 64 and is driven thereby.

A cup blank advanced between the feed rolls 101 and 102 is fed onto the stationary 35 table 33 beneath the guard plate 35 and is guided along one edge of a blank guide bar 111 and against a stop bar 112. The bars 111 and 112 are both mounted upon the stationary table 33 (Fig. 1). The cup blank is thus advanced into the dotted line position of Figure 1 ready to have a film of 40 glue applied or stamped thereon in a pre-determined configuration through the opening 34 in the table 33. The glue is applied or stamped on a portion of the cup blank by means of a pad 113 made of rubber or 45 other suitable material and shaped as illustrated in Figure 6 in order that a film of glue of a desired shape may be stamped on the cup blank. The glue applying pad 50 is mounted on the top of a pad holding plate 114 secured on a bracket plate 115 having an angled flange 116 which is bolted or otherwise secured to a slidable bar 117. The bar 117 is vertically slidable in a groove of 55 a channel bar 118 rigidly secured in a recess in a frame section 119. Retaining strips 120 are secured to the flanges of the channel bar 118 and overlap the slide bar 117 to retain the same in place. 60 Integrally formed on the frame section 119 is a shelf 121 upon which a glue box 122 is supported. Rotatably supported in the glue box 122 is a glue feed roller 123 which is mounted on a shaft 124, one end 65 of which projects through a bearing 125.

The bearing 125 is formed on the upper end of a bracket arm 126 rigidly secured to a transverse board or bar 127 secured across the front of the machine to the frame section 119. A small sprocket wheel 128 is 70 fixed on the projecting end of the shaft 124 and is driven by means of a chain 129 which is trained around the large sprocket wheel 63. The glue feed roller 123 is provided with a scraper blade 130 which is mounted 75 upon a bar 131 secured upon uprights 132 formed on opposite sides of the glue box 122. A cam block or bar 133 is fixed to one side of the scraper blade 130 and is positioned to be contacted by the tapered ends 80 of adjustable wing headed screws 134. A glue drip apron 135 is secured to the rear end of the glue box 122, as illustrated in Figure 16. 85

The glue applying pad 113 is reciprocated by a cam controlled mechanism clearly shown in Figure 4. Formed on the lower end of the slide bar 117 is a collar 136 having a bolt 137 projecting therethrough and provided with a lock nut 138. Engaged on the lower end of the adjustable bolt 137 is an angle member 139 to one arm of which is pivotally connected the upper end of a toggle or link 140. The lower end of the link 140 is pivoted in one end of an arm or lever 141, the other end of which is pivoted on a transverse shaft 142 which is journaled in bearings formed on the lower ends of a pair of bracket arms or supports 143 which are integral with the frame upright members 57. The lever 141 comprises a pair of parallel bars (Fig. 6) separated by a spacer 144 on the shaft 142. Pivoted between the bars of the lever 141 is the lower end of an arm 145, the upper end of which is provided with an integral fork 146 (Fig. 4), the prongs of which project on opposite sides of a transverse shaft 147 which is journaled in bearings 148 formed on the lower portions of the bracket plates 57. A roller 149 is mounted on one side of the forked arm 145 and is disposed to act in a cam groove 150 of a cam wheel 151 secured upon the shaft 147. The shaft 147 is rotated from a gear 152 secured on one end thereof and meshing 100 with the gear 62. 110

Keyed or otherwise secured to the shaft 142 adjacent the inner sides of the stationary frame arms 143 are a pair of levers 153 to the upper ends of which are pivotally connected the ends of a pair of long arms or bars 154. The arms 154 are also pivoted to a pair of blocks 155 which are slidable on rods 156 secured to the machine frame upright plates 57 and to stationary blocks 157. Rotatably supported by the slidable blocks 155 is a rubber pad gluing roll 158 having a plurality of longitudinal passages therein, as 120 illustrated in Figure 4. Fixed on one end 130 of the shaft of the roll 158 is a roller 159 125

adapted at a certain time in the travel of the roll 158 to come into contact with and roll over an angle rail 160 to cause rotation of the gluing roll 158.

5 Fixed on the shaft 142 to the outside of one of the bracket arms 143 is a crank arm 161 having a boss or block 162 formed on one side thereof to coact with a set or stop screw 163 mounted in a boss 164, formed on 10 one of the bracket arms 143 (Fig. 2) to limit the forward movement of the pad gluing roll 158. Connected eccentrically to the gear 152 is one end of a bar 165, the other end of which is provided with a 15 slotted head 166 which engages over a pin 167 on the crank arm 161. A spring 168 is connected to the pin 167 and to a pin 169 on the eccentric bar 165, to hold the pin 167 against the inner end of the slot in the head 20 166.

A mechanism is also provided to prevent the pad gluing roll 158 from being moved into engagement with the glue feed roll 123 when the blank guide plate 35 is swung upwardly away from the table 33 by operating 25 the handle 88 when the latch bolt 94 is retracted. This mechanism comprises a long crank arm 170 which is integrally formed on the sleeve 80 on which the short crank 30 arm 81 is formed. Pivoted to the end of the crank arm 170 is the upper end of a rod 171, the lower end of which slidably projects through a passaged boss or arm 172 integrally formed on one of the stationary 35 35 bracket arms 143. The lower flattened end of the rod 171 is adapted to be positioned in front of the stop screw 163 to limit the swing of the crank arm 161, thereby also limiting the forward movement of the glue 40 applying roll 158 and holding the same out of contact with the glue feed roll 123 when the blank guide plate 35 is raised.

After a cup blank has been fed from the cup blank magazine onto the stationary 45 table below the plate 35 the cup blank is stamped with a film of glue and is then ready to be advanced or transferred onto the reciprocating blank feed table 31, when in its retracted position, by a cup blank 50 transfer mechanism operable from the shaft 26. The cup blank transfer mechanism comprises a crank arm 173 fixed on the shaft 26 to the outside of the plate 47 and having the end thereof pivotally connected 55 to one end of a connecting rod 174. The other end of the connecting rod 174 is pivoted to the end of a short arm 175 of a bell crank having a long arm 176 integral with said short arm. The bell crank 175—176 is secured on a stud shaft 177 which is journaled in a bearing in the transverse bar 127 and is provided with an integral head 178 on the inner end thereof to the outside of the bell crank member 175—176. Engaged 60 on the outer end of the stud shaft 177 is a

brake roll or collar 179 around which spring controlled brake band segments 180 and 181 are engaged. The spring controlled brake mechanism is adapted to control the swing of the bell crank 175—176. Mounted on the 70 end of the long bell crank arm 176 is a curved rack 182 which meshes with a gear segment 183 formed on one end of a sleeve 184 rotatably engaged on a short shaft or pin 185 supported in the end of a curved 75 arm 186, the lower end of which is rotatable on the shaft 177 adjacent the bell crank 175—176. Secured to the sleeve 184 is a movable gripper or jaw 187 in which the head end of a stationary gripper or jaw 188 80 is disposed. The head of the upper gripper 188 is keyed on the shaft 185 (Fig. 11) to hold the upper gripper in a horizontal position. Also keyed upon the shaft 185 adjacent the arm 186 is one end of a toggle or 85 link 189, to the other end of which the upper end of a long bar or lever 190 is pivoted. The lower end of the lever 190 is pivoted to a stud secured to the transverse frame bar 127. 90

When the blank grippers engage a cup blank on the stationary table and transfer the blank on the retracted reciprocating table 31 a pair of pivoted stop arms 191 (Fig. 6) mounted on a rod 192 are swung 95 upwardly into a vertical position by means of a spring 193. The blank is deposited upon the supporting pins 41 and 43 and upon the fingers 39 out of contact with the table so that the film of glue on the blank 100 will not come in contact with the table proper. When the blank is moved onto the supporting pins of the reciprocating table the blank is pulled underneath a resilient spring arm 194 and beneath the tips of 105 spring arms 195. The spring arms 195 are shaped as illustrated in Figures 1 and 3 and have the upper ends thereof secured to a bar 196 secured transversely of the machine upon the top of the frame yoke 107. The 110 spring arm 194 is mounted on a block 197 secured on one end of a rotatable rod or shaft 198 supported by the arms of a yoke member 199 secured to the machine frame yoke 107 (Fig. 7). Secured to the end of the shaft 198 (Fig. 5) is an arm 200 having a roller 201 supported on the end thereof for coaction with the periphery of a cam 202 which is keyed on the end of the shaft 65. 115

Connected with the cup forming die 8 is an air supply pipe 203 having an automatically controlled valve therein adapted at a predetermined time to supply a blast of air through the cup forming die 8 to blow a finished cup off of said die into a cup stacking mechanism at the front end of the machine. When a finished cup is discharged from the forming die 8 it is discharged into the mouth of a curved guide chute 204 secured to the machine frame and having the lower end at 120 125 130

tached to a vertical cup collecting tube 205 into which a slidable arm 206 projects to support a cup receiving holder within the tube. Pivoted to the bottom of the cup 5 guide chute 204 is a notched shutter 207 adapted to be swung into a closed position as illustrated in Figure 17 to prevent cups from entering the tube 205.

The arm 206 is formed on a sleeve 208 which is slidable upon a guide rod 209. Also formed on the sleeve 208 is a guide arm 210 which engages against a vertical tube or pipe 211 in which a counterweight is suspended by means of a cord or cable 212. 15 The cord 212 is trained over a pulley wheel 213 and is attached to the arm 206 (Fig. 17). The pulley wheel 213 is mounted on a shaft 214 which is supported on a bracket arm 215 mounted on top of the pipe 211. A ratchet wheel 216 is supported on the shaft 214 adjacent the pulley wheel 213 and has a pawl 217 coacting therewith and operable by a bar 218 operated from the machine.

The operation is as follows: 25 The cup forming machine is adapted to be operated by means of a driving belt driven from any suitable source of power and trained around the loose pulley 5. To start the machine the driving pulley is shifted by any suitable mechanism over onto the fastened pulley 4 thereby transmitting a drive to the main drive shaft 3 and to the gear 6 thereon. The cup forming die 8 is connected to be driven from the main drive shaft 3 in a manner similar to that illustrated and described in my copending application for patent for an "automatic cup forming machine", filed October 28, 1918, Serial No. 259,986. A beveled gear mounted 30 on the shaft on which the forming die 8 is mounted is adapted to rotate the beveled gear 20 and the shaft 14 on which the cup presser die 15 is mounted. The cup forming dies 8 and 15 are separated at the beginning 35 of a cup forming operation due to the action of the cam 10 on the beveled roller 11.

A stack of prepared cup blanks, of a shape similar to that illustrated in dotted lines in Figure 1, is placed in the blank holding 50 magazine between the upright guides 71 and 76 with the lowermost cup blank resting upon the bosses 72 and upon the arms 79. The blanks are so shaped that they clear the inclined guide plate 77. The delivery of a 55 cup blank from the bottom of the stack is accomplished by means of the rotatable feed reel 66-67 which carries the friction pads 68. The feed reel is rotated by the gear 64 which is in mesh with the gear 62 on the 60 shaft 61 on which the beveled gear 60 is mounted to be operated by the beveled gear 59. The beveled gear 59 is operated from the gear 53 which is directly in mesh with the large gear 7 operated by the drive gear 65 6 on the shaft 3. When the feed reel is ro-

tated, the friction pads 68 thereof are brought into contact with the bottom surface of the lowermost cup blank and slide said blank from the magazine between the feed rolls 101 and 102. As the blank is being removed from the magazine the trailing tip thereof is first pulled out of engagement with the pin 74 and is then guided under the inclined guide plate 77. The lowermost blank in the magazine is thus delivered to 75 the feed rollers and the stack of blanks falls by gravity.

As illustrated in Figure 8, the feed rollers 101 and 102 are driven by the meshing gears 104 and 105 which in turn receive their drive from the gears 108 and 110 which are operated by the gear 64. The cup blank received between the rollers 101 and 102 is fed forwardly thereby onto the stationary table 33 and beneath the guide plate 35 on which the electric heater 100 is mounted. As the cup blank is fed onto the stationary table 33 one edge of the cup blank slides along the guide bar 111 until the advance edge of the cup blank comes into contact with the stop bar 112. The cup blank is thus properly centered on the stationary table with a portion of the cup blank on which glue is to be applied disposed over the table opening 34 in the field of operation 90 of the glue applying pad 113.

The glue is carried in the tank or box 122 in which the glue feed roller 123 operates. The glue feed roller is rotated from the shaft 61, the chain 129 and the gear 128 which rotates the shaft 124 on which the feed roller is mounted. Excess glue carried upwardly by the feed roller from the glue box 122 is scraped from the roller by means of the scraper blade 130. The scraper blade 130 is adjustable with respect to the feed roller by means of the tapered screws 134 which coact with the beveled block 133 secured on the scraper blade. 100

At this stage in the operation the glue applying pad 113 is in its lowered position (Fig. 16) and the pad gluing roller 158 is in its retracted position as illustrated in Fig. 4. Meshing with the gear 62 is the larger gear 152 to which the eccentric bar 165 is connected. The eccentric bar 165 thus acts to actuate the crank arm 161 to swing the same toward the set screw 163. The shaft 142 is thus partially rotated in one direction to cause the levers 153 to swing forwardly thereby actuating the arms 154 to cause the blocks 155 to slide forwardly on the guide rods 156 and thereby advance the roller 158 which is caused to rotate when the roller 159 comes in contact with the angle rail 160 (Figure 9). The advancing and rotating roller 158 is thus advanced over the retracted pad 113 into contact with the rotating glue feed roller 123. The roller 158 is thus supplied with a coating of glue and 110 115 120 125

as it is retracted by the reverse motion of eccentrically operated arms 154 and the levers 153 a coating of glue from the roller 158 is applied to the pad 113. With the 5 return movement of the glue applying roller 158 the cam member 151 on the rotating shaft 147 co-acting with the roller 149 on the arm 145 is positioned to cause an upward swing of the levers 141 thereby elevating the toggle member 140 and causing the same to push the bracket plate 115 upwardly. The glue pad 113 is thus advanced upwardly through the table opening 34 and stamps a film of glue on the under surface 10 of the cup blank which is heated by the heater 100 so that the glue will readily adhere thereto. The shape of the film of glue is of course similar to the shape of the pad 113 as illustrated in Figure 6 and is applied to a particular portion of the cup blank.

With the application of the film of glue to the cup blank, the pad 113 is retracted. The glue stamped cup blank is now ready 25 to be transferred from the stationary table 33 onto the reciprocating table 31. When the dies 8 and 15 are rotating the table 31 is reciprocated by means of the lever 30. The lever 30 is oscillated from the shaft 26 0 which is rocked back and forth by the crank arm 25 connected eccentrically by the link 24 to the gear 7 to receive a drive therefrom. When a glue stamped cup blank is on the stationary table 33 the table 31 starts 35 to move back permitting the spring controlled stop arms 191 (Figure 6) to swing upwardly into a vertical position by the action of the spring 193. The lever 30 now acts to gradually retract the table 31 beneath the stationary table 33. As the table 40 moves into its retracted position the crank arm 173 acts on the connecting rod 174 to swing the bell crank 175-176 from the dotted line position of Figure 10 toward 45 the full line position thereby causing the rack 182 to act on the gear segment 183 to move the lower gripper jaw 187 into closed position upwardly against the bottom surface of the cup blank to clamp a portion of 50 the cup blank between the gripper jaws 187 and 188. After the jaws are closed the bell crank 175-176 acts on the curved arm 186 to move the grippers jaws toward the full line position of Figure 10. The members 55 189 and 190 act to cause the gripper jaws to move through horizontal planes when a gripped cup blank is being transferred from the stationary table onto the reciprocating table.

60 With the retraction of the table 31, the gripped cup blank is pulled off of the stationary table 33 and is delivered onto the cup blank supporting pins 41 and 43 and onto the supporting fingers 39 free from 65 contact with the table and a little in advance

of the stops 40 and 44. As the blank is transferred onto the reciprocating table 31, it is conducted beneath the tips of the resilient arms 194 and 195 which frictionally contact the upper surface of the cup blank to pull 70 the cup blank backwardly against the stops 40 and 44 when the table 31 starts to advance thereby properly centering the cup blank on the table. When the cup blank is being transferred onto the table 31 the cam 75 202 (Figure 7) acts on the roller 201 to cause the shaft 198 to partially rotate thereby causing the presser arm 194 to swing upwardly away from the table 31 to permit the cup blank to be moved beneath the same 80 onto the reciprocating table. With the advance of the table 31, the action of the cam 202 permits the presser arm 194 to be lowered into frictional engagement with the cup blank. In addition to the spring arms 194 85 and 195 which act to pull the cup blank into a centered position on the table 31, the upright arms 191 also act to push the cup blank backwardly on the advancing table and are then lowered by the advance end of said 90 table which passes over the same. The centered cup blank is now advanced into the field of operation of the dies 8 and 15 to be gripped thereby as the table 31 again starts to move back. As the advance end of the cup blank is projected between the separated dies 8 and 15 the raised portion of the cam 10 rotates away from the roller 11 thereby permitting the sleeve 12 to be lowered 95 so that the presser die 15 moves downwardly toward the forming die 8 clamping the advance portion of the cup blank between the dies. The cup blank is thus automatically fed into the field of operation of the forming dies.

100 The cup blank is now formed around the forming die 8, the main portion of the blank first being formed into a cup around the die 8 after which the glued portion of the blank is gradually wrapped around the body of the cup to reinforce the same. As the glued portion of the cup blank is wrapped around the conical cup, the spiral groove 16 of the presser die 15 engages over the margin 17 105 (Figures 18 and 19) of the cup blank thereby preventing any pressure from being applied to said margin 17. The glue is accordingly not pressed out from below the margin 17 and sticking of the formed cups, one within the other, is thus obviated. The completed cup is thus formed on the die 8 ready to be automatically discharged from the forming die by a blast of air from the air pipe 203 similar to the arrangement disclosed in my co-pending application for Patent Serial Number 259,986 for an "Automatic cup forming machine" filed October 28, 1918.

110 When a cup is finished the presser die 15 is of course first separated from the forming 115 120 125 130

die by the action of the beveled cam 10 on the roller 11. The cup being released by the presser die it is discharged from the forming die and falls into the curved chute 204 and then enters the top of the receiving tube 205 to be received by the cup holder provided within the tube and supported on the end of the movable arm 206. The curved chute 204 is provided to afford a long path between the forming die 8 and the cup stacking tube 205 so that there will be a short lapse of time sufficient to permit the glue to set before the cup enters the stacking tube 205 and is pressed against other cups within the tube.

Each time a cup is delivered into the tube 205 the movable supporting arm 206 is lowered a predetermined distance by the action of the bar 218 which operates the pawl 217 and the ratchet wheel 216. When the tube is filled by a stack of nested cups the shutter 207 is moved into closed position across the bottom of the chute 204 to receive cups while the stack of cups in the tube 205 is removed. It will thus be noted that the machine need not be stopped during the time the tube 205 is emptied.

If at any time during the operation of the machine a cup blank should become caught or crumpled between the guide plate 35 and the stationary table 33 it is only necessary for the operator to pull on the handle 99 to pull the latch bolt 94 from the full line position of Figure 13 into the dotted line release position of said figure. The plate 35 is thus readily released and may be swung upwardly by means of the handle 88 about the shaft 87 (Figure 15) until the pin 86 strikes against the bar 82. When the plate 35 is swung upwardly the cam block 84 acts against the pin 83 thereby pulling the bar 82 forwardly. Forward movement of the bar 82 acts to swing the crank arm 81 upwardly to partially rotate the shaft 78 where by the lifter arms 79 (Figure 1) are swung upwardly to raise the stack of cup blanks in the blank holding magazine out of the field of operation of the blank feed reel pads 68 so that no cup blanks will be delivered from the magazine to the blank feed rollers 101 and 102 when the plate 35 is raised and the machine continues operating.

Forward movement of the bar 82 also causes the crank arm 170 on the sleeve 80 to swing downwardly from the position illustrated in Figure 2 to lower the rod 171 and push the flattened lower end thereof in front of the stop screw 163. The lower end of the rod 171 is thus positioned to be contacted by the boss 162 on the crank arm 161 thereby shortening the forward throw of the levers 153 on the shaft 142 so that the arms 154 will not move the glue applying roller 158 forward far enough to come into contact with the glue feeding roller 123. No glue

from the roller 123 is distributed to the glue applying roller 158 when the plate 35 is raised.

It will be noted that when it becomes necessary to raise the blank guide plate 35 that the cam block 84 automatically acts to cause elevation of the cup blanks in the magazine so that the feed of cup blanks into the machine is discontinued as well as the feeding of glue to the roller 158 and from said roller to the glue stamping pad 113.

I am aware that numerous details of construction may be varied through a wide range without departing from the principles of this invention, and I therefore do not purpose limiting the patent granted otherwise than necessitated by the prior art.

I claim as my invention—

1. In a cup forming machine the combination with a pair of cup forming dies, and means for feeding an adhesived cup blank between said dies to be formed into a cup, one of said dies having a spiral groove therein to engage over the margin of the adhesived portion of the cup blank so that no pressure will be applied to said margin during the forming of the cup.

2. In a cup forming machine the combination with a cup forming die, of a presser die adapted to co-act therewith and having a peripheral groove therein.

3. In a cup forming machine the combination with a cup forming die, of a presser die adapted to co-act therewith and having a spiral groove in the peripheral surface thereof.

4. In a cup forming machine the combination with a pair of cup forming dies, of means for feeding an adhesived cup blank between the dies to be formed into a cup, one of said dies being formed so that no pressure will be applied to the margin of the overlapped portion of the cup blank when the blank is being formed into a cup by said dies.

5. In a cup forming machine the combination with a forming die and a spirally grooved presser die, of feed mechanisms for feeding a cup blank between the forming die and the presser die, and means for stamping a film of adhesive on the cup blank before it is fed between said dies.

6. In a cup forming machine the combination with a rotatable conical forming die and a grooved conical presser die, of a blank feeding mechanism, means for stamping a film of adhesive on a cup blank and means for advancing the stamped cup blank between said dies.

7. In a cup forming machine the combination with a pair of cup forming dies, of a stationary table, means for feeding a cup blank onto said stationary table, means for stamping a film of adhesive on the cup blank, a reciprocating table, and mechanisms

for transferring the adhesived cup blank from said stationary table onto the reciprocating table to be advanced between the cup forming dies.

8. In a cup forming machine the combination with a pair of cup forming dies, of a stationary table having an opening therein, means for feeding a cup blank onto said stationary table, an adhesive applying pad, means operated from the machine for causing the pad to stamp a film of adhesive on the cup blank on said stationary table, a movable table, and a mechanism for gripping the stamped cup blank and transferring the same onto the movable table to be advanced between the forming dies.
9. In a cup forming machine the combination with a pair of cup forming dies, of a stationary table having an opening therein, a cup blank holding magazine, means for removing a cup blank from the magazine and delivering the same onto the stationary table, an adhesive applying pad, means for operating the same to stamp a film of adhesive on a portion of the cup blank, a gripper mechanism, a reciprocating table, means for operating the gripper mechanism to cause the same to grip the stamped cup blank and transfer the same onto the reciprocating table to be advanced between the forming dies.

10. In a cup forming machine the combination with a pair of cup forming dies of a stationary table, a guide plate positioned above said stationary table, means for feeding a cup blank between the stationary table and said guide plate, an adhesive applying pad operable from the machine for stamping a film of adhesive on a portion of the cup blank, a reciprocating table, means for transferring the stamped cup blank from between the stationary table and said guide plate onto the reciprocating table to be fed between the forming dies.

11. In a cup forming machine the combination with a pair of forming dies, of a stationary table having an opening therein, a guide plate above the stationary table, means for feeding a cup blank onto the stationary table below the guide plate, an adhesive applying pad, means for supplying the pad with adhesive, a mechanism for operating the pad to cause the same to stamp a film of adhesive on a portion of the cup blank, and means for feeding the stamped cup blank between the forming dies.

12. In a cup forming machine the combination with a pair of forming dies, of a stationary table having an opening therein, a guide plate above the table, a heater on said guide plate, means for feeding a cup blank onto the stationary table below the guide plate to be heated by said heater, an adhesive applying pad, mechanisms for supplying the pad with adhesive, means for

actuating the pad to cause the same to stamp a film of adhesive on a portion of the cup blank, a reciprocating feed table, a gripper device for transferring the adhesived cup blank onto the reciprocating table to be fed between the forming dies, and members on the reciprocating table for holding the adhesived cup blank out of direct contact with said blank reciprocating table.

13. In a cup forming machine the combination with a pair of cup forming dies, of a stationary table having an opening therein, a guide plate above the stationary table, a heater supported on said guide plate, means for feeding a cup blank onto the stationary table below the guide plate to be heated by said heater, an adhesive applying pad, a roller for supplying the pad with adhesive, a cam actuated mechanism for causing the pad to stamp a film of adhesive on a portion of the cup blank, a reciprocating table operable from the machine, pin members projecting from said reciprocating table, and a gripper mechanism operable from the machine for transferring the adhesived cup blank from the stationary table onto the pin members on said reciprocating table to be fed between the forming dies.

14. In a cup forming machine the combination with a pair of cup forming dies, of a stationary table having an opening therein, a guide plate above the stationary table, means for feeding a cup blank onto the stationary table below the guide plate, an adhesive applying pad, an adhesive feed roller, an adhesive distributing roller, means operated from the machine for moving the adhesive distributing roller into contact with the adhesive feed roller and then causing said adhesive distributing roller to supply the pad with adhesive, a mechanism operated from the machine for causing the pad to stamp the cup blank, a reciprocating table operable from the machine, and a gripper mechanism adapted to transfer the stamped cup blank from the stationary table onto said reciprocating table to be fed between the forming dies.

15. In a cup forming machine the combination with a pair of cup forming dies, of a stationary table, a plate positioned thereabove, means for feeding a cup blank onto the stationary table below said plate, an adhesive applying pad, an adhesive tank, a feed roller therein, an adhesive distributing roller, means for reciprocating the same to first engage the adhesive feed roller and then apply adhesive onto said pad, a cam controlled mechanism for causing the pad to stamp the cup blank with a film of adhesive, and mechanisms operable from the machine for feeding the stamped cup blank between said cup forming dies.

16. In a cup forming machine the combination with a stationary table, a plate there-

- above, means for feeding a cup blank onto the stationary table below the plate, and adhesive applying pad, an adhesive tank, a feed roller rotatable therein, an adhesive distributing roller, means for reciprocating the same to cause said adhesive distributing roller to first engage the adhesive feed roller and then apply adhesive to said pad, means for reciprocating the pad to cause the same to stamp the cup blank with a film of adhesive, and a cam mechanism operable from the machine for operating said pad reciprocating means.
17. In a cup forming machine the combination with a stationary table, a plate thereabove, means for feeding a cup blank between said table and plate, an adhesive tank, a feed roller rotatable therein, an adhesive distributing roller, means for reciprocating the same to contact the feed roller and receive a supply of adhesive therefrom, means for rotating the adhesive distributing roller during reciprocation, a slidible pad adapted to be supplied with adhesive by having the adhesive distributing roller roll thereover, and a cam mechanism for reciprocating the pad to cause the same to stamp the cup blank with a film of adhesive.
18. In a cup forming machine the combination with a table, means for feeding a cup blank thereto, a pad for applying adhesive to said cup blank, a lever mechanism for operating the pad, a forked member pivoted on the lever mechanism, a cam member operable from the machine, and a roller on said forked member engaged with the cam member to cause reciprocation of the pad at predetermined intervals.
19. In a cup forming machine the combination with a table, of a plate thereabove, means for feeding a cup blank between the table and plate, a mechanism for stamping a film of adhesive on the cup blank, and means for heating the cup blank so that the adhesive will readily adhere thereto.
20. In a cup forming machine the combination with a table, of a plate positioned thereabove, a locking mechanism for holding said plate in a predetermined position and adapted to be released to permit raising of said plate, means for feeding a cup blank between the table and plate, and a pad operable from the machine for forcing the cup blank against said plate to stamp a film of adhesive on the cup blank.
21. In a cup forming machine the combination with a table, of a magazine for holding a stack of cup blanks, means for feeding a cup blank from the magazine onto said table, a plate above the table, a locking means for holding the plate in a set position, and reciprocating means for applying a film of adhesive on the cup blank.
22. In a cup forming machine the combination with a table, of a magazine for holding a stack of cup blanks, means for feeding a cup blank from the magazine onto said table, means for stamping a film of adhesive on a portion of the cup blank, a plate above the table affording a stop for the cup blank when being stamped, a mechanism for moving the plate away from the table, and lifter means operated by the raising of said plate to cause lifting of the stack of cup blanks in the magazine out of the field of operation of the cup feeding means.
23. In a cup forming machine the combination with a table, of a magazine for holding a stack of cup blanks, means for feeding a cup blank from the magazine onto said table, means for stamping a film of adhesive on the cup blank, a plate above the table affording a stop for the cup blank when being stamped, means for releasing the plate, a handle for swinging the plate away from the table, a lifter mechanism in the magazine, and means connected to the lifter mechanism adapted to be actuated with the raising of the plate to cause the lifter mechanism to raise the stack of cup blanks in the magazine so that no cup blanks will be fed onto the table when the plate is raised.
24. In a cup forming machine the combination with a magazine for holding a stack of cup blanks, of a table, feed rollers between the magazine and said table, a feeding device adapted to advance cup blanks from the magazine between said feed rollers to be advanced onto said table, and means for raising the stack of cup blanks in the magazine out of the field of operation of the feeding device.
25. In a cup forming machine the combination with a magazine for holding a stack of cup blanks, of a table, a plate thereabove, feed rollers between the magazine and said table, a feeding device adapted to advance a cup blank from the magazine between said feed rollers to be delivered onto said table, lifter means for raising the stack of cup blanks in the magazine, an adhesive feed roller, a pad for stamping a film of adhesive on the cup blank on said table, an adhesive distributing roller, means for advancing the same into contact with the feed roller to receive a supply of adhesive and then apply the adhesive to the pad, means for raising the plate, and mechanisms for actuating the lifter means and limiting the movement of the adhesive distributing roller so that it will not contact with the adhesive roller when said plate is raised.
26. In a cup forming machine the combination with a table, of a plate thereabove adapted to be moved away from the table, means for feeding a cup blank between the table and plate, a stamping pad for stamping adhesive on the cup blank, an adhesive supply mechanism for the pad, and mecha-

nisms for stopping the feeding of blanks and the supplying of adhesive to the pad when the plate is raised.

27. In a cup forming machine the combination with a table, of a plate positioned thereabove, a latch mechanism for holding the plate locked in a set position and a handle attached to said plate for swinging the plate away from the table when the latch mechanism is released.

28. In a cup forming machine the combination with a table, of a plate positioned thereabove, a latch mechanism for holding the plate locked in a set position, and a handle attached to said plate for swinging the plate away from the table when the latch mechanism is released, and a cam operated device connected with the lifter mechanism adapted to be operated by the raising of the plate to cause the lifter mechanism to raise the cup blanks in said magazine out of the field of operation of the blank feeding means.

29. In a cup forming machine the combination with a magazine for holding a stack of cup blanks, of rotatable means for delivering cup blanks from the magazine, and a lifter device in said magazine adapted to be operated to raise the stack of cup blanks out of the field of operation of said rotatable means.

30. In a cup forming machine the combination with a pair of cup forming dies, of a stationary table, means for delivering a cup blank thereto, a reciprocating table, stops thereon, means for transferring the cup blank from the stationary table onto the reciprocating table, a spring arm adapted to engage the cup blank and pull the same rearwardly on the reciprocating table against said stops when the reciprocating table is advancing to feed the cup blank between the forming dies, and means for automatically elevating the spring arm when the reciprocating table is being retracted.

31. In a cup forming machine the combination with a pair of forming dies, of a stationary table, means for feeding a cup blank thereto, means for applying adhesive to the cup blank, a reciprocating table, means for transferring the cup blank from the stationary table onto the reciprocating

table, stops on said reciprocating table, and pivoted means controlled by the reciprocating table adapted to push the cup blank against said stops to center the cup blank before it is fed between the forming dies.

32. In a cup forming machine the combination with a pair of forming dies, of a reciprocating table, means for delivering a cup blank onto said table and means controlled by the table for centering the cup blank on the table before the cup blank is delivered to the forming dies.

33. In a cup forming machine the combination with a reciprocating table, of means for delivering a cup blank thereto, and means below the table adapted to move into a position when the table is retracted to cause centering of the cup blank on the table when the table is advanced.

34. In a cup forming machine the combination with a stationary table, of a reciprocating table, means for delivering a cup blank onto the stationary table, grippers, a gear segment on one of said grippers, a rack member co-acting with the gear segment and means for operating the rack member to first cause the grippers to engage the cup blank on the stationary table and then transfer the cup blank onto the reciprocating tables.

35. In a cup forming machine the combination with a stationary table, of a reciprocating table, means for delivering a cup blank onto the stationary table; grippers, a gear segment on one of said grippers, a rack member co-acting with the gear segment, means for operating the rack member to first cause the grippers to engage the cup blank on the stationary table and then transfer the cup blank onto the reciprocating table, and mechanisms connected with the grippers for causing the same to move through horizontal planes when delivering a cup blank to the reciprocating table.

In testimony whereof I have hereunto subscribed my name in the presence of two subscribing witnesses.
